UNITED STATES PATENT OFFICE.

FREDERIC AUMONIER, OF LONDON, ENGLAND.

DESIGN FOR WALL-PAPER.

SPECIFICATION forming part of Design No. 22,957, dated December 5, 1893.

Application filed October 20, 1893. Serial No. 488,751. Term of patent 3½ years. Registered in England December 21, 1892, No. 204,613.

To all whom it may concern:

Be it known that I, FREDERIC AUMONIER, (trading as Wm. WOOLIAMS & Co.,) a subject of the Queen of Great Britain, and a resident of 110 High Street, near Manchester Square, London, England, have invented a new and original Design for Wall-Paper, (registered in Great Britain on the 21st of December, 1892, No. 204,613,) of which the following is a specification.

The design for wall paper as represented by the accompanying drawing consists of wavy lines of acanthus like leaves running in a vertical direction, a basket of clematis and daisy like flowers and leaves being arranged in the center of the opened curved portions of the wavy line of acanthus leaves, flowers like daisies being arranged garland fashion beneath the bottom and at the sides of the basket. The baskets on the several open curved portions are arranged diagonally with each other.

I claim—

The design for wall paper substantially as shown and described.

The 10th day of March, 1893.

FREDERIC AUMONIER.
